US00D800786S

(12) **United States Design Patent** (10) **Patent No.:** **US D800,786 S**
(45) **Date of Patent:** **** Oct. 24, 2017**

(54) **HYDRAULIC CONTROL UNIT**

(71) Applicant: **Eaton Corporation**, Cleveland, OH (US)

(72) Inventor: **Matthew G. Fox**, Ceresco, MI (US)

(73) Assignee: **Eaton Corporation**, Cleveland, OH (US)

(**) Term: **15 Years**

(21) Appl. No.: **29/594,158**

(22) Filed: **Feb. 16, 2017**

Related U.S. Application Data

(63) Continuation of application No. 29/535,729, filed on Aug. 10, 2015, now Pat. No. Des. 779,561, which is a continuation-in-part of application No. 29/533,526, filed on Jul. 17, 2015, now Pat. No. Des. 779,560.

(57) **CLAIM**

The ornamental design for a hydraulic control unit, as shown and described.

DESCRIPTION

FIG. 1 is a front perspective view of a hydraulic control unit showing the new design.

FIG. 2 is a rear perspective view of the hydraulic control unit of FIG. 1.

FIG. 3 is a first end view of the hydraulic control unit of FIG. 1.

FIG. 4 is a second end view of the hydraulic control unit of FIG. 1.

FIG. 5 is a top plan view of the hydraulic control unit of FIG. 1.

FIG. 6 is a bottom plan view of the hydraulic control unit of FIG. 1.

FIG. 7 is a first side view of the hydraulic control unit of FIG. 1; and,

FIG. 8 is a second side view of the hydraulic control unit of FIG. 1.

Any portion of the hydraulic control unit shown in broken lines is for the purpose of illustrating environmental structure that forms no part of the claimed design.

1 Claim, 6 Drawing Sheets
